(57) **CLAIM**

The ornamental design for a multi-pocket storage rack, as shown and described.

DESCRIPTION

FIG. 1 is a front, left side and top perspective view of a multi-pocket storage rack showing my new design; FIG. 2 is a front elevational view thereof;

FIG. 3 is a left side elevational view thereof, the right side elevational view being a mirror image;

FIG. 4 is a rear elevational view thereof;

FIG. 5 is a top plan view thereof; and,

FIG. 6 is a bottom plan view thereof.
